J. S. GARD.

FIREPROOF WALL.

APPLICATION FILED APR. 21, 1908.

916,141.

Patented Mar. 23, 1909.

UNITED STATES PATENT OFFICE.

JOHN S. GARD, OF OAKLAND, CALIFORNIA.

FIREPROOF WALL.

No. 916,141.

Specification of Letters Patent. Patented March 23, 1909.

Application filed April 21, 1908. Serial No. 428,385.

To all whom it may concern:

Be it known that I, JOHN S. GARD, citizen of the United States, residing at Oakland, in the county of Alameda and State of California, have invented certain new and useful Improvements in Fireproof Walls, of which the following is a specification.

This invention comprehends certain new and useful improvements in fire proof walls or partitions for buildings, and the invention has for its object an improved construction of wall or partition of this character which will be light, durable and strong and which is composed of comparatively few parts, and which may be cheaply manufactured and easily assembled.

With this and other objects in view as will more fully appear as the description proceeds, the invention consists in certain construction, arrangements and combination of parts that I shall hereinafter fully describe and then point out the novel features in the appended claims.

For a full understanding of the invention, reference is to be had to the following description and accompanying drawings in which:

Figure 1 is an elevation of a portion of a wall or partition constructed in accordance with my invention; Fig. 2 is a transverse sectional view thereof; Fig. 3 is a horizontal section upon the line 3—3 of Fig. 1; Figs. 4 and 5 are detail sectional views of the joint connection between the studs, anchor plates, and channeled top plates. Fig. 6 is a detail top plan view of one of the anchor plates; Fig. 7 is a detail view of a modified form of separating plate; and, Fig. 8 is another detail view of a modified form of anchor plate.

Corresponding and like parts are referred to in the following description and indicated in all the views of the accompanying drawings by the same reference characters.

My improved fire proof wall or partition embodies a series of tubular metallic studs 1 the upper ends of which support anchor plates 2 which may be formed of all metal. These anchor plates 2 have tongues 3 depending therefrom and extending downwardly and fitting within the studs at the upper ends thereof, the anchor plates being thereby held in place to prevent their accidental displacement. The ends of the anchor plates 2 are turned upwardly and, as indicated at 4, are of inverted V-shape preferably as shown, said ends 4 constituting re-

taining ears between which the top plates 5 fit, said top plates being thereby supported by the studding and extending from stud to stud to form upper horizontal braces for the partition or wall.

The tiles 6 of my improved wall or partition have embedded therein wire netting reinforcements 7 some of the wires of which protrude out from the rear face of the tiling 65 and are lashed around the studs 1 as indicated at 8 so as to securely hold the tiles in place.

9 designates a series of separating plates that are interposed between the front and rear tiles at the joint thereof, the ends of said plates being recessed so as to fit snugly around opposite sides of the studs, and thereby hold the studs securely in position and braced by the plates and tiles. The abutting edges of the adjacent tiles are beveled as indicated at 10 so as to effect a secure joint. As a preferred method of setting up my improved wall or partition, one tier of tiles is held in place, such tier or section is run up to 80 the ceiling by means of a double straight edge made for the purpose, the same not being shown herein, as it forms no part of my invention. The separating or spreader plates 9 are then slipped into position against opposite sides of the studs and are wedged into place, and the studs are then slipped into the small holes which are formed in the concrete floor of the building. Then the tie wires of this section are lashed to the studs. The opposite section of the wall is then built up, the back tie wires being tied as the rear tile is put in place.

Fig. 7 illustrates a modified form of separating plate designated 9^a, constructed of vitreous material reinforced with wire netting.

Fig. 8 illustrates in detail that form of anchor-plate designated 2^a that is designed to connect one partition with another, said plate being provided with a depending flange 2^b engaging one face of the wall and depending tongues 3^a engaging the opposite face of the wall.

From the foregoing description in connection with the accompanying drawings it will be seen that I have provided a very simple, durable and efficient construction of fire proof wall or partition which may be cheaply manufactured and the parts thereof readily assembled, and which will be light, durable and strong, and which will not possess that

sound carrying property which is a disadvantage of most structures of this type, and which will also effect an economy in that it will save two coats of plastering, the finishing coat going on the tile.

Having thus described the invention, what is claimed as new is:

1. A fire proof wall or partition, comprising a series of tubular studs, anchor plates formed with depending tongues fitting within the upper end of said studs and also formed with upwardly projecting ears projecting above the studs, top plates supported upon said anchor plates, and fitting within or be-

tween said ears, and tiles secured to said studs.

2. A fire proof wall or partition, comprising a series of tubular studs, anchor plates having depending tongues fitting within the upper ends of said studs, and supported thereby, top plates supported by said anchor plates, and tiles secured to said studs.

In testimony whereof I affix my signature in presence of two witnesses.

JOHN S. GARD. [L. S.]
